UNITED STATES PATENT OFFICE.

JESSE S. PEVEAR, OF SCHENECTADY, NEW YORK, ASSIGNOR TO GENERAL ELECTRIC COMPANY, A CORPORATION OF NEW YORK.

SWITCH-OPERATING MECHANISM.

No. 806,709.

Specification of Letters Patent.

Patented Dec. 5, 1905.

Application filed February 27, 1905. Serial No. 247,440.

To all whom it may concern:

Be it known that I, JESSE S. PEVEAR, a citizen of the United States, residing at Schenectady, county of Schenectady, State of New York, have invented certain new and useful Improvements in Switch-Operating Mechanisms, of which the following is a specification.

The present invention relates to switches which are actuated selectively—as, for instance, in apparatus arranged for operation on both alternating and direct currents, wherein different switches are employed for connecting the apparatus to the source of current-supply, according as the current which is being supplied is alternating or direct. Such mechanism is particularly applicable to electric-railway service in which a portion of the line is supplied with alternating current and another portion with direct current. In this latter instance plural switch apparatus is almost always necessary, for the reason that the alternating current is supplied to the trolley at a high potential, and the potential is reduced to the proper value by means of a transformer carried upon the car itself, and since the direct current cannot pass through the transformer separate switches must be provided for use on alternating and direct currents, respectively.

It is of advantage to make changes in the internal connections of the motors themselves in passing from one form of current to the other, inasmuch as a motor wound for efficient operation on alternating current generally requires some change either in the control-circuit or in the connections of the motor-windings for most efficient operation upon direct current, and a controlling-switch or commutating-switch is provided for making the desired changes in the motor-windings themselves when changing from one current to another. For this reason, also, it is desirable to have a plurality of main switches in order that current may not be supplied to and through the commutating-switch except when it and one of the main switches are in corresponding positions.

In my prior application, Serial No. 220,166, for improvements in motor control there is disclosed a system of the character specified in which the two main switches are interlocked, so that both may not be closed at the same time. The handle for operating these switches serves also to operate the commutating-switch,

the arrangement being such that the handle 55 cannot be removed from engagement with the main switches except when they are both open. This construction makes it necessary for the motorman when changing over from alternating current to direct current, or vice 60 versa, to first open both main switches before the commutating-switch may be operated to its proper running position and prevents him from afterward again moving the commutating-switch unless and until the main switches 65 are again both open.

The manual operation of the main switches of course requires more or less attention on the part of the motorman and requires some time for its accomplishment. Also where it 70 is necessary to operate the main switch manually the car must be brought to a stop or else a comparatively long dead section of trolley must be employed for separating the alternating-current wire from the direct-current 75 wire in order to allow sufficient time for operating the switch mechanism while the car continues in motion.

One object of the present invention is to so construct and arrange main-switch mechanism 80 of the character described that a main switch is automatically closed by current from the source of supply and immediately opens when the flow of current is interrupted.

A further object of the present invention is 85 to so arrange the automatic operating means for switch mechanism of the character described that only one of a plurality of switches may be closed at a time.

A further object of the present invention 90 consists in a simple and novel construction and arrangement of parts whereby a number of switches are selectively operated, according as the current supplied to the actuating means is alternating or direct.

Further objects of the present invention will appear in connection with the following description thereof.

One form of the present invention is illustrated in the accompanying drawing, which 100 illustrates diagrammatically a portion of a car equipment and automatically-actuated switch mechanism for connecting it to the source of current-supply.

Similar reference characters will be used 105 throughout the specification and drawing to indicate like parts.

X indicates a trolley-wire or third rail at the

point of junction of the portions 1 and 2, which are energized by direct and by alternating currents, respectively. 3 indicates an insulated or dead section connecting the live sections 1 and 2. 5 T and T' are trolleys or other current-collecting devices, adapted to make contact with the trolley-wire or third rail X. D and A are two main switches carried by the car and are respectively adapted to connect the motor and 10 control apparatus to the collecting device when direct current or alternating current is being supplied. E and E' are commutating-switches, which may be simple switches for connecting the control apparatus to trolley or 15 may have other functions similar to those of the commutating-switch in my aforesaid application. C and C' are controllers. All these parts may have any usual or desired construction, since they in themselves form no part 20 of the present invention, except as will be hereinafter specified.

The switch D consists of a movable member d, adapted to engage with fixed contacts d', together with an auxiliary contact device, 25 which consists of a movable contact member d², arranged to engage with fixed contacts d³. These contacts may all be placed within an oil-receptacle of the character shown in my aforesaid application, and the movable members d and d² may both be carried by single stem d⁴, although this particular arrangement of parts is not essential, since the main and auxiliary switches may have any suitable construction and may be operatively connected 30 together in any suitable manner, whereby the auxiliary contacts are caused to open when the main contacts are closed. Switch A is similar to the switch D and comprises members a to a⁴, which correspond, respectively, to 35 the members d to d⁴.

When the main switch D is closed, current is supplied from the trolley through wire 5, contacts d and d', wire 6 to fixed contact e of commutating-switch E, and to a similar contact in commutating-switch E', if two commutating-switches are employed. Similarly, if the main switch A is closed current will be supplied from the trolley through wire 7, contacts a a', transformer F, wire 8, to contact e' 45 of the commutating-switch E. The commutating-switch is provided with a third fixed contact e², which may be connected to a fixed contact e on the controller C. The commutating-switch is provided with movable contact-segments e³ and e⁴, so arranged that when the switch is thrown in one direction fixed contacts e and e² are connected together, and when the switch is in the other running position contacts e' and e² are connected together, 50 in the one case supplying the motor and control apparatus with direct current and in the other with alternating current.

The means for operating the main switches automatically and selectively is as follows: 55 One of each of the sets of fixed auxiliary con-

tacts d³ and a³ is permanently connected to the trolley by means of the wire 9 and preferably a resistance r. Normally when no current is being supplied to the trolley both main switches are open, and therefore both auxiliary switches closed. Assuming that trolley T receives direct current, this current will flow through the resistance r, wire 9, the auxiliary switch associated with main switch A, reactance R, switch S, coil D' to ground, 70 thereby energizing coil D'. The coil D' controls the switch D in any suitable manner—as, for instance, by acting upon a magnetic core 10, which is operatively connected to the stem d⁴ by suitable lever mechanism 11, so constructed and arranged that when the coil D' is energized the core is moved in a direction to close the main switch. So long as the current-flow is uninterrupted the main switch will be maintained in its closed position; but 75 should the current be interrupted the switch will automatically resume its normal open position. The current passing through wire 9 originally branched so as to pass through the auxiliary contact associated with the main 80 switch D, as well as through the auxiliary contact of the main switch A, but served no useful purpose, passing simply through resistance r², the primary of the transformer f, to ground. As soon, however, as the main 85 switch D is closed the auxiliary switch associated therewith is opened and no further flow of current can take place through the transformer f. If the trolley T is now moved toward and upon section 2, the direct current 90 to coil D' is interrupted and switch D opens. The alternating current which tends to energize this coil is so checked by the reactance R that there is not a sufficient flow to actuate the core 10. Switch D therefore remains 95 open and its auxiliary switch is closed. The current branches as before and passes through these auxiliary contacts d² and d³, resistance r², primary of transformer f, to ground. The secondary of transformer f is thereupon energized and current flows therefrom through one side of switch S, through coil A', to ground, completing the circuit through the secondary of the transformer which has one terminal grounded. The action of the coil A' 100 upon the core 12 and the lever mechanism 13, connecting this core to this stem a⁴, closes the main contacts of switch A and opens the auxiliary contacts. It is noted that as soon as one main switch is closed the actuating-circuit for the other switch is broken, so that 105 both switches cannot be closed at the same time. 110

By the foregoing arrangement a simple and compact switch mechanism is provided which 115 is automatic and certain in its action and which obviates the necessity for a long dead section of trolley-wire or third rail or of bringing the car to a stop when it becomes necessary to operate the switches. 120 130

- Although I have described one form of the present invention with great particularity I do not desire to limit the present invention to the specific details illustrated, since the present invention in its broader aspects may be embodied in various other forms, and in the appended claims I intend to cover all embodiments of the present invention other than the particular form illustrated.
10. What I claim as new, and desire to secure by Letters Patent of the United States, is—
1. In combination, a supply-conductor, a pair of normally open switches, electromagnetic actuating means for said switches normally connected to said supply-conductor and arranged to actuate said switches selectively according as the current supplied is alternating or direct, and means associated with one of said switches for controlling the other.
  2. In combination, a supply-conductor, a pair of main switches, electromagnetic actuating means for said switches normally connected to said supply-conductor and arranged to actuate said switches selectively according as the current supplied is alternating or direct, and an auxiliary switch associated with each of said main switches for controlling the actuating-circuit of the other main switch.
  3. In combination, a supply-conductor, a pair of normally open switches, electromagnetic actuating means for said switches normally connected to said supply-conductor and arranged to actuate said switches selectively according as the current supplied is direct or alternating, and an interlock between the said switches for preventing the closing of one switch when the other is closed.
  4. In combination, a supply-conductor, a pair of switches, an electromagnet associated with each of said switches for controlling its operation, a connection including a reactance between one of said electromagnets and said supply-conductor, and a connection including

a transformer between the other of said switches and said supply-conductor, whereby 45 the switches are actuated selectively according as the current supplied is alternating or direct.

5. In combination, a supply-conductor, a pair of switches, an electromagnet associated 50 with each of said switches for controlling its action, a connection including a reactance between one of said electromagnets and said supply-conductor, a connection including a transformer between the other of said electromagnets and said supply-conductor, and auxiliary contacts controlled by each switch and arranged in the connection of the controlling-magnet of the other switch.

6. In combination, a supply-conductor, 60 electric apparatus adapted to be connected to said supply-conductor, a pair of switches for connecting said apparatus to said supply-conductor, means for selectively actuating said switches according as the current supplied is 65 direct or alternating, and means associated with each switch for controlling the other switch.

7. In combination, a supply-conductor, 70 electric apparatus, a pair of switches for connecting said apparatus to said supply-conductor, an electromagnet associated with each of said switches for controlling its operation, a connection including a reactance between one of said electromagnets and said supply-conductor, and a connection including a transformer between the other of said switches and supply-conductors whereby the switches are actuated selectively according as the current supplied is alternating or direct. 75 80

In witness whereof I have hereunto set my hand this 24th day of February, 1905.
